DESIGN FOR A PENCIL FOR TELEPHONE DIALS

Olivia White, San Francisco, Calif.

Application June 18, 1945, Serial No. 120,175

Term of patent 7 years

(CL. D74—24)

To all whom it may concern:

Be it known that I, Olivia White, a citizen of the United States of America, residing at San Francisco, in the county of San Francisco and State of California, have invented a new, original, and ornamental Design for a Pencil for Telephone Dials, of which the following is a specification, reference being had to the accompanying drawing, forming a part thereof.

Fig. 1 is a top plan view of a pencil for telephone dials showing my new design;

Fig. 2 is a perspective view thereof; and
Fig. 3 is an elevational view of the pencil, which should present substantially the same appearance when viewed from any angle in elevation.

I claim:

The ornamental design for a pencil for telephone dials, substantially as shown and described.

OLIVIA WHITE.
